UNITED STATES PATENT OFFICE.

JOHN M. TAYLOR, OF HARTFORD, CONNECTICUT.

CLAMP.

1,221,774.

Specification of Letters Patent.

Patented Apr. 3, 1917.

Application filed November 23, 1915. Serial No. 63,046.

To all whom it may concern:

Be it known that I, JOHN M. TAYLOR, a citizen of the United States, residing at Hartford, in the county of Hartford and State of Connecticut, have invented certain new and useful Improvements in Clamps, of which the following is a specification.

This invention relates to clamps, the object of the invention being to provide a device of this nature which can be operated with ease and facility, which is thoroughly strong and which will hold the work rigid.

In the drawings accompanying and forming part of the present specification I have shown in detail one convenient form of embodiment of the invention which I will fully set forth in the following description. I do not restrict myself to this particular disclosure; I may depart therefrom in several respects within the scope of the invention defined by the claims following said description.

Referring to said drawings:

Figure 1 is a top plan view of a clamp involving my invention.

Fig. 2 is a horizontal sectional view of the same.

Fig. 3 is a longitudinal section on the line 3—3 of Fig. 1, looking in the direction 30 of the arrow.

Fig. 4 is an end elevation as seen from the left in Fig. 1, and,

Fig. 5 is an end elevation as seen from the right in said Fig. 1, of said clamp.

Fig. 6 is a horizontal section on an enlarged scale of the automatically locking jaw, a part of each of the rods showing.

Like characters refer to like parts throughout the several views.

I prefer to provide two jaws such for instance as those denoted in a general way by 2 and 3 respectively. In the present case the jaw 2 is manually operable or adjustable, and while the jaw 3 is manually settable, it has in connection with it means of a suitable nature whereby it can be locked automatically in the requisite position. Any suitable means may be provided for supporting and guiding the two jaws. For this purpose I have shown the parallel rods 4 and 5, the rods extending through the jaws and the latter being slideable on the rods.

The jaw 3 as shown is chambered which presents a convenient way for receiving locking means. The locking means may vary radically, although the plates 6, 7, 8 and 9

answer satisfactorily in this connection, there being illustrated two pairs of plates. The plates 6 and 7 coöperate and have perforations which receive the rod 4. The plates 8 and 9 coact and are likewise perforated to receive the rod 5. The perforations or holes in the respective pairs of plates are at approximately right angles to the longitudinal axes thereof and in diameter are greater than the diameters of the respective rods which permits the tipping of the plates so that they can be moved alternatively to locking and releasing positions as will hereinafter appear. The inner plates 70 6 and 8 fulcrum on their inner surfaces midway of the length thereof against the bearings 10 and 11. The jaw 3 has interiorly the sockets 12 to receive the protractile or push springs 13. These springs 75 bear at their outer ends against the bottoms of the respective sockets and at their inner ends against the outer plates 7 and 9 so as to tip the plates on the bearing portions 10 as shown in Fig. 2 for example. 80 It will be clear that the perforations in the respective locking plates 6, 7, 8 and 9 are to the outer sides of the axes of motion of the respective plates and that the springs bear against said outer sides. The consequence is that the springs automatically constantly tilt the plates to the position shown in Fig. 2 where the walls of the perforations or holes in the plates can bite against the rods 4 and 5 to an extent sufficient to effectually preclude accidental movement of the 90 jaw 3. In fact when the locking plates are set, it is practically impossible to move the jaw 3. Said jaw 3 is represented as straddled by the part 14 constituting a suitable 95 manipulating member and which may have an actuator as 15 rigid therewith. For instance the two parts might be riveted together. The outer side of the jaw 3 has a slot 16 through which this actuator 15 projects, the actuator normally engaging the inner ends of the two outer plates 7 and 9. Through the actuator 15 and through the branches of the forked manipulating member 14, the rivet 17 may extend, the rivet 100 105 projecting through slots 18 elongated in the direction of movement of the actuator 15.

In Fig. 6 the locking plates 6, 7, 8 and 9 are shown as being in their locking relation by full lines, the manipulating member 14 110 and actuator 15 being in their retracted positions also in full lines. To release the

jaw 3, the following procedure may be adopted: The manipulating member 14 is thrust inward in the direction of the arrow in Fig. 6, thus correspondingly moving the actuator 14. The actuator 14 in constant engagement with the plates 7 and 9 will move said plates 7 and 9 inward and the latter in turn will cause a like movement of the plates 6 and 8, the motion continuing until the several locking plates are at approximately right angles to the guide and supporting rods 4 and 5 as shown by dotted lines in said Fig. 6. This brings the perforations in the pairs of locking plates into register and the walls of the perforations practically free of the rods 4 and 5, thus freeing the jaw 3 so that the latter can be easily slid along said rods. When the jaw is in the necessary position, the manipulating portion 14 is released at which point the springs 13 acting against the outer sides of the plates 6, 7, 8 and 9 immediately move said plates to the full line position in said Fig. 6 so that the walls of the perforations in the plates can bite against the two rods to firmly secure the jaw 3 in its adjusted position.

The supporting and guide rods 4 and 5 as shown are maintained in parallelism and in rigid relation with each other in some suitable manner as by the bridge or cross piece 19 which may consist of substantially duplicate sections connected as by rivets 20, the sections of the bridge piece having grooves 21 which mate with each other and which receive the bent end portions 22 of the rods 4 and 5.

To effect the adjustment of the jaw 2, the nut 23 and screw 24 may be provided, the threads of the two as illustrated being left-handed threads. The nut 23 has a circumferential channel or groove 23' to receive the projecting portion 25 which at its sides abuts against the walls of said groove 24. This construction provides for the free turning of the nut but prevents the movement of the nut in the direction of its axis of rotation or in the direction of the longitudinal axis of the screw 24. The inner end 26 of the screw is plain, the plain portion being driven into a socket 27 in the outer side of the jaw 2 and the stock of the jaw being swaged as at 24' into the groove of the thread of the screw 24. It, therefore, follows that if the nut 23 be turned, the screw 24 will be endwise moved to thereby effect corresponding movement of the jaw 2, the direction of movement of the jaw depending upon the direction in which the nut 23 is turned. As represented the nut has an outward extension 28 perforated to freely receive the sides of the loop-like handle 29. This handle is made of the necessary stock and is doubled on itself to present a loop closed at one end and open at the other, the sides of the open loop being in parallelism and extending

through the bores in the nut-extension or projection 28. After the open loop is thus connected with the nut or its extension, the open end thereof is closed, the loop where the sides thereof abut when closed being covered by the split tubular member 30. It will be clear that the handle or loop 29 can be freely moved oppositely so that either end thereof is accessible for turning the nut 23 to effect the action of the screw 24 and hence of the jaw 2.

As may be inferred the clamp is susceptible of general use. It will be assumed that it is to be used for clamping together two previously glued together pieces of work. In this case the jaw 3 is freed from the supporting and guide rods 4 and 5 by the inward movement of the manipulating member 14 in the manner already described after which the jaw 3 is moved along the rods until it is spaced from the companion jaw 2 a distance a little more than the width of the work at which point the manipulating portion 14 is freed so that the jaw 3 can be locked to said rods in the manner also previously set forth. Following this the rods 4 and 5 are brought over or under the work as may be required with the work received between the two jaws at which time the handle 29 is operated to run the jaw 2 toward the coöperating jaw 3, so that the jaws can jointly clamp the work.

The rod 5 it will be noticed is longer than the rod 4. The extended end of the rod 5 is equipped with a nut 5' constituting a suitable stop fitting the threaded portion 5" of said rod 5, the thread 5" being sufficiently long as to permit the nut 5' to abut against the jaw 3 when the jaw is on both rods. There are cases where the stock should be received within the two jaws 2 and 3. In this event the nut 5' will be backed off sufficiently to permit the jaw 3 to be slid off the rod 4, and when the work is between the two rods, the jaw 3 will be fitted on the rod 4 and the nut 5' run forward until it abuts against the jaw 3.

What I claim is:

1. A clamp comprising a support, a jaw slideable on the support, a locking member directly supported by the jaw, spring means acting against the locking member to cause the latter to engage the support and thereby lock the jaw in an adjusted position, means independent of the work engaging portion of the jaw for moving the locking member to releasing position, a second jaw on the support, and manually operable means for causing the movement of the second jaw toward and from the first jaw.

2. A clamp comprising a pair of parallel rods, a chambered jaw slideable on the rods, locking plates in the chambered jaw having openings for the respective rods, springs acting constantly against the locking plates to

- hold the same in locking position, a part independent of the work engaging portion of the jaw supported outside the jaw and provided with means extending into the jaw 5 to act against the locking plate to move the same to releasing position on movement of said part, a second jaw slideable on the rods, and means for moving the second jaw toward and from the first jaw.
- 10 3. A clamp comprising a pair of parallel guide rods, a chambered jaw supported for slideable adjustment by the rods, plates in the chambered jaw perforated for the passage of the respective rods, springs inclosed 15 by the jaw, acting constantly against the respective plates at their outer portions to normally force the plates yieldingly into locking engagement with the respective rods, the plates between their ends fulcruming 20 against the jaw, a bifurcated member straddling the outer portion of the jaw, said jaw having a slot in its outer portion and the bifurcated member having a projecting portion extending into the jaw to engage the 25 inner ends of the locking plates to move said locking plates to releasing position on a predetermined movement of the bifurcated member, a second jaw through which the rods pass, and means for moving the second 30 jaw toward and from the first jaw.
4. A clamp comprising supporting and guide rods disposed in parallelism, a jaw slideable on said rods, means for locking said jaw in a predetermined position, a second 35 jaw slideable on the rods toward and from the other jaw, a bridge piece in sections to receive the rods, and means for fastening the sections of the bridge-piece together and for also holding the rods in place therebetween, a nut rotatively supported by the bridge piece between the sections thereof, the nut being peripherally grooved between its 40 ends and the bridge piece having means extending into the groove of the nut to prevent movement of the latter in the direction 45 of its axis of rotation, and a manually operable screw threaded through the nut and having a rigid connection with said second jaw.
5. A clamp comprising a pair of parallel rods, a chambered jaw slideable on the rods, locking plates in the chambered jaw having openings for the respective rods, springs acting against the outer ends of the locking plates and tending constantly to maintain 50 the same in locking relation with the respective rods, the plates between their ends fulcruming against the jaw, the work engaging portion of the jaw being in constant fixed relation with the plate fulcrum parts 55 of the jaw, means carried by the jaw to act against the inner portions of the plates to move the plates to releasing position, a second jaw carried by said rods, and manually operable means for moving said second jaw 60 toward and from the companion jaw.
6. A clamp comprising a pair of parallel guide rods, a chambered jaw supported for slideable adjustment by the rods, plates in the chambered jaw perforated for the passage 65 of the respective rods, springs inclosed by the jaw, acting constantly against the respective plates at their outer portions to normally force the plates yieldingly into locking engagement with the respective rods, the 70 plates between their ends fulcruming against the jaw, the inner face of the jaw being rigid with the body thereof, means supported by the jaw to engage the inner ends of the two plates and movable to simultaneously cause 75 the two plates to free the rods, a second jaw through which the rods extend, and means for moving the second jaw toward and from the first jaw.

In testimony whereof I affix my signature 80 in presence of two witnesses.

JOHN M. TAYLOR.
